PULL FOR FURNITURE

La Verne E. Clayton, Rockford, Ill., assignor to Amerock Corporation, Rockford, Ill., a corporation of Connecticut

Continuation of design application Ser. No. 9,067, Oct. 19, 1967. This application Dec. 11, 1967, Ser. No. 9,741

Term of patent 14 years

(Cl. D10—8)

FIG. 2 is a top view of the pull.

FIG. 3 is a sectional view of the pull taken along the line 3—3 in FIG. 1.

FIG. 4 is an enlarged side view of the pull as seen from the left in FIG. 1.

FIG. 5 is an enlarged sectional view of the pull taken along the line 5—5 in FIG. 1.

This application is a continuation of my co-pending application Ser. No. D. 9,067 filed Oct. 19, 1967, and now abandoned.

I claim:

The ornamental design for a pull for furniture, as shown.
